UNITED STATES PATENT OFFICE.

RALPH GREENWOOD, OF ALTOONA, PENNSYLVANIA.

IMPROVEMENT IN FIRE-BOXES FOR LOCOMOTIVE-ENGINES.

Specification forming part of Letters Patent No. 25,009, dated August 9, 1859.

To all whom it may concern:

Be it known that I, RALPH GREENWOOD, of Altoona, in the county of Blair and State of Pennsylvania, have invented a new and useful Improvement in Fire-Boxes for Steam-Boilers; and I do hereby declare that the following is a full, clear, and exact description of the same, reference being had to the annexed drawings, marking a part of this specification, in which—

Figure 1 is a side view of a locomotive fire-box. Fig. 2 is a front sectional view of the same, taken in the line *x x*, Fig. 3. Fig. 3 is a side sectional view of the same, taken in the line *y y*, Fig. 2.

Similar letters of reference indicate corresponding parts in the several figures.

This invention, although applicable to all steam-boilers, is more especially designed for coal-burning locomotives.

The object of this invention is to consume the inflammable products of imperfect combustion and at the same time present to the direct action of the fire a larger area of heating-surface, thereby economizing in fuel and augmenting generally the efficiency of coal-burning locomotives.

The invention consists in the employment or use of a "mid-feather" or water-chamber placed directly over the fire and provided with a plurality of small flues, which form a communication between the fire-box and a gas-chamber above, into which, as well as into the fire-box below, air is admitted through hollow stay-bolts at the sides and end of the boiler and the desired object attained.

To enable those skilled in the art to fully understand and construct my invention, I will proceed to describe it.

A represents the fire-box of a locomotive provided with double walls, which form water-spaces *a*, communicating with the boiler *B*.

C is a mid-feather or water-chamber, which is placed within the fire-box directly over the fire. This mid-feather extends the whole width and length of the fire-box and forms a partition or barrier between the fire-box and what may be termed a "gas-chamber," *D*, which communicates with flue-tubes *b*. The water-chamber *C* communicates at its front end with the boiler *B* by a vertical tube, *c*, and said water-chamber is provided with hol-

low stay-bolts *d*, by which a communication is formed between the fire-box and the gas-chamber, as shown clearly in Figs. 2 and 3. This mid-feather or water-chamber *C* may be constructed of boiler-plate and arranged precisely similar to the double-walled water-spaces *a* of the fire-box; or perforated fire-bricks may be used with advantage, although the water-chamber would be preferable, on account of its economy in increasing the heating-surface of the boiler.

The gas-chamber *D* is made to communicate with the external air at one or both sides by means of perforations *e*, formed by hollow stay-bolts, the outer orifices of which are provided with a register, *E*. The fire-box *A*, also, is made to communicate at each side with the external air by means of hollow stay-bolts *f*, the outer orifices of which are also provided with a register, *F*. The two registers *E F* at each side of the fire-box are connected by a lever, *G*, as shown clearly in Figs. 1 and 2.

The water-spaces *a* at the front end of the fire-box and gas-chamber are also provided with hollow stay-bolts *g* to admit air to the fire-box and gas-chamber, and the fire-box is also provided with hollow stay-bolts *h* at its back end.

By having the registers *E F* connected by the lever *G*, as shown, the openings *e f* of the gas-chamber and fire-box may be contracted or enlarged simultaneously, according to the amount of oxygen required.

The operation is as follows: The draft from the fire being through the hollow stay-bolts *d* of the mid-feather or water-chamber *C*, the products of combustion, or, rather, the products of imperfect combustion, are divided, so as to readily combine with the oxygen admitted into the gas-chamber *D*, and the temperature of the gases, when combined with oxygen, will be sufficiently high to cause them to ignite and be consumed. Oxygen is also admitted into the fire-box through the hollow stay-bolts *g h f*, so as to produce a perfect and even distribution of draft through the mid-feather or water-chamber and a more perfect union of the gases and oxygen.

I am aware that a mid-feather has been used in connection with an air-chamber as a means for distributing air into the fire-box, and I do not claim such device when placed

in relation with an air-chamber for such purpose; but I am not aware that a mid-feather has been used singly and simply as a distributor to divide or spread the inflammable products of imperfect combustion and render their union with the oxygen admitted into the chamber more perfect than it would otherwise be.

I claim therefore as new and desire to secure by Letters Patent—

1. The mid-feather C, when used in connection with a gas-chamber, D, and fire-box A,

provided with openings e f g h, the parts being arranged relatively with each other to operate substantially as and for the purpose set forth.

2. The two registers E F, when applied to the orifices of the gas-chamber and fire-box and connected by a lever, G, to operate simultaneously, as and for the purpose set forth.

RALPH GREENWOOD.
